CLAIM

The ornamental design for a front panel of a motorhome, as shown and described.

DESCRIPTION

FIG. 1 is a perspective view of the front panel of a motorhome showing my new design;
FIG. 2 is a top plan view thereof;

FIG. 3 is a front end elevational view thereof;
FIG. 4 is a right side elevational view thereof, with the left side being a substantial mirror image thereof;
FIG. 5 is a rear end elevational view thereof; and
FIG. 6 is a bottom plan view thereof.
